UNITED STATES PATENT OFFICE

117,461

DESIGN FOR A COMBINATION TOP, GAUGE, AND GUIDE BARS FOR WOODWORKING MACHINES

Herbert E. Tautz, Milwaukee, Wis., assignor to
Delta Manufacturing Company, Milwaukee,
Wis.

Application November 23, 1938, Serial No. 81,319

Term of patent 14 years

To all whom it may concern:

Be it known that I, Herbert E. Tautz, a citizen of the United States, residing at 620 East Vienna Avenue, in the city and county of Milwaukee and State of Wisconsin, have invented a new, original, and ornamental Design for a Combination Top, Gauge, and Guide Bars for Woodworking Machines, of which the following is a specification, reference being had to the accompanying drawing, forming part thereof.

Fig. 1 is a perspective view of a combination top, gauge, and guide bars for woodworking machines, showing my new design; and

Fig. 2 is a fragmentary side elevational view of the gauge shown in Fig. 1, with the gauge bar shown broken away.

The dominant features of my design reside in the portions shown in full lines.

I claim:

The ornamental design for a combination top, gauge, and guide bars for woodworking machines, as shown and described.

HERBERT E. TAUTZ.
